Patent is directed to a device for attaching a sheet of carbon paper to the front of a typewriter platen, so that when a sheet of paper is placed over the carbon paper, the characters typed on the sheet will be reproduced on the sheet of paper. The device is particularly adapted for use with a typewriter having a horizontal bar which is secured to the front of the platen, and which has a pair of arms extending forwardly therefrom.

SUMMARY ATTACHMENT FOR TYPEWRITERS

Victor J. Ferguson, Saskatoon, Saskatchewan,
Canada

Application November 6, 1944, Serial No. 562,061

1 Claim. (Cl. 197—138)

My invention relates to an attachment for typewriters, an object thereof being to provide a device of the character herewithin described by the use of which cheques, receipts, invoices, ledger pages or the like may be typed upon at the same time as a summary is typed via a sheet of carbon paper. By means of my attachment, the said summary is held in fixed position subject to rotation line by line while the cheque or other document is inserted or removed. Upon my summary sheet, the symbols typed upon the cheques or other documents, are duplicated in columnar form.

A further object of my invention is to provide a device of the character herewithin described which is readily attachable to any make of typewriter and may therefore be sold as an accessory, the item being of conspicuously simple manufacture, positive as to function, and being one which will give long service without any need for attention.

With the above more important objects in view and such other minor objects as may appear as the specification proceeds, my invention consists essentially in the arrangement and construction of parts all as hereinafter more particularly described, reference being had to the accompanying drawings, in which:

Figure 1 is a plan view of the rear part of a typewriter showing the conventional platen and paper rest plate with my attachment in situ.

Figure 2 is an enlarged sectional elevation illustrating my attachment in situ and also illustrating the manner in which documents are positioned in relation to the attachment when in use.

Figure 3 is a detail illustrating my margin aligning stop as viewed at 3—3 of Figure 1.

Figure 4 is an illustration of a portion of a sheet of purchase form.

Figure 5 is an illustration of a summary.

In the drawings like characters of reference indicate corresponding parts in the different figures.

By the use of my attachment I am able to type via a carbon sheet, a summary in columnar form of the entries made upon cheques, receipts, invoices and the like, a process which is obviously impossible in a practical sense on an ordinary typewriter because of the impossibility of maintaining the position of a carbon-impressed summary while inserting and removing a cheque form or the like overlying the same. To amplify in this context, it will be recognized that when the conventional paper gripping rollers or bails are loosened or moved into spaced relationship with

respect to the platen, all the sheets wrapped around the platen are loosened simultaneously. Consequently, the withdrawal or adjustment of one of them causes movement and misalignment of the others.

By means of my attachment I have overcome this difficulty, and proceeding therefore to describe my invention in detail, the same will be seen to consist of a horizontal bar 1 which is secured at the ends thereof in angle brackets 2 fastened to the front face 3 of a paper rest plate 4 in slightly spaced relationship to the plate as illustrated in Figures 2 and 3. Positioned adjacent the ends of the bar 1 are forwardly projecting and downwardly inclined arms 5, these arms being rotatably secured to the bar by means of the sleeve portions 6.

The arms are downwardly spring loaded by virtue of the springs 7 associated therewith and the configuration of which is clearly illustrated in Figure 1, the forward ends of the arms being also provided with transverse bearings 8 through which extend horizontal and slidable rods 9 each having at the ends thereof small rollers 10.

The rollers 10 bear downwardly against the conventional platen or cylinder 11, and in preparation for writing a series of cheques for instance of which it is desired a summary shall be kept, I first insert a summary sheet 12 covered by a conventional carbon paper 13 the sensitive surface of which will be in contact with the front surface of the summary. The summary will preferably though not necessarily be inserted over or above the bar 1, and after becoming wrapped around the forward surface of the platen, it will be trained beneath the inner rollers 10, which may if desired be lifted with the arms 5 for the purpose, so that the summary and carbon sheet are gripped between the rollers 10 and the platen as illustrated in Figures 1 and 2.

The cheque form or other document 14 may now be inserted, such document being preferably introduced beneath the bar 1, or in other words between the bar and the front surface of the paper rest plate. The conventional rollers or bails 15 are loosened by actuation of the conventional paper release 16 and the cheque form or the like lined up with respect to the writing point 17. It is to be particularly noted however that the cheque form is not gripped by my rollers 10, but is free of same and overlies them as clearly illustrated in the accompanying Figure 2.

From the foregoing, it will be obvious that when a line has been typed upon the cheque form or other document, and a carbon copy there-

of duly impressed upon the summary, the said cheque form or the like may readily be released from the machine by loosening the bails 15, which operation, owing to the function of my attachment will not cause movement of the summary. After the cheque form or other document has been removed, the summary can be moved up one or more lines as desired by rotation of the conventional platen knobs 18, after which the next cheque form or the like may be typed upon.

For purposes of orientation, it is to be understood that the elements identified 19 are the conventional paper clamps which move upon the rod 20, these devices being springless, and simply provided to hold the edges of sheets of paper in wrapping contact with the forward part of the platen surface.

In association with my device I also provide a margin aligning stop 20' to facilitate the common or mutual alignment of the summary and overlying sheets (cheque forms or the like), this element being best illustrated in the accompanying Figure 3 from which it will be seen that the same is slideable upon the bar 1 and consists of a pair of diametrically opposed and projecting lug portions 21 and 22, the portion 21 being intended to act as a margin stop or a guide for the sum-

mary, while the portion 22 performs a similar function for the overlying sheets and as will be seen, projects into the space 23 between the bar 1 and the rest plate 4.

5 Since various modifications can be made in my invention as hereinabove described and many apparently widely different embodiments of same made within the scope of the claim without departing from such spirit and scope, it is intended that all matter contained in the accompanying specification shall be interpreted as illustrative only and not in a limiting sense and I desire only such limitations placed thereon as are specifically expressed in the accompanying claim.

10 15 What I claim as my invention is:

The combination with a conventional type-writer platen, paper gripping rollers and a paper rest plate, of a horizontal bar secured at the ends thereof to the front face of said rest plate in 20 slightly spaced relationship, a pair of spaced, forwardly projecting and downwardly spring loaded arms rotatably mounted on said bar, bearings on the free ends of said arms, horizontal slideable rods in said bearings parallel with said bar, and 25 rollers on the ends of said rods bearable against said platen as and for the purpose specified.

VICTOR J. FERGUSON.
